UNITED STATES PATENT OFFICE.

RANDOLPH ARBUCKLE, OF LA GRANGE, ILLINOIS.

SCREEN.

Application filed October 28, 1927. Serial No. 229,354.

My invention relates to screens of the type commonly employed in window and door frames and has for its general object the provision of a novel window screen adapted to rid a room of insects and particularly flies.

Another object of my invention is to provide a window screen for the purpose indicated that will be simple in construction, 10 efficient in operation, and suitable for manufacturing and selling at low cost.

Other objects and advantages of the method and construction herein employed will appear more fully in the hereinafter 15 specification, when taken in connection with the accompanying drawings, in which:—

Figure 1 is a front elevation of my device.

Figure 2 is a vertical section taken on line 20 2—2 of Figure 1.

Figure 3 is an enlarged detail view of the fly escape.

With more particular reference to the drawings wherein similar characters of reference indicate corresponding parts in the several views, A designates a window frame and B my novel screen therein. The screen B comprises the mesh 10, stiles 11 and 12, the moulding 12', the bottom rail 13, center rail 14, and top rail 15, wherein is located 30 the fly escape passageway C.

The window frame A comprises the drip cap 16, head casing 17, sill 18, sub-sill 19, upper and lower sashes 20 and 21 respectively, window stool 22, parting stop 23, blind stop 24, and window stop 25.

As an important feature of my invention the fly escape passageway C, having the oblique walls 26, 27, is particularly adapted to admit rays of light, either direct or reflected, from the sun, to enter the diagonal opening 27',—these rays being perceptible from the inner side of the screen.

The mode of operation and functioning 45 of my novel screen will now be apparent upon referring to the drawings, in connection with the following brief description.

As is well known, flies and most species of insects are strongly attracted by light. If a room is darkened by lowering of the blinds therein practically all of the flies will be found between the window panes or screens and the blinds. Also it is a fact of every day observation that flies upon the interior

of a door and window screen generally direct their course to the upper part thereof. In the present instance any flies that may be upon the mesh 10 will be attracted by beams of daylight entering the opening 27' of the fly passageway C and will enter 55 therein, thereby finding their way into the outer atmosphere. In this manner, a room may in great measure be rid of flies without resorting to any direct means to destroy them. It is to be noted that from the outside 60 the passageway will appear dark to insects, which consequently will not be attracted to enter therein. In this respect the fly escape is substantially similar in theory to a tunnel, wherein rays of light on 65 the outside are strongly accentuated to persons on the inside, while to an outside beholder the tunnel will have a dark aspect in which objects may scarcely, if at all, be seen. I have in practice found that the method 70 herein described and illustrated is very efficient for the purpose indicated.

While the above embodiment is a preferred one, I do not desire to be understood as limiting myself to the precise details as so set forth, but wish to avail myself of such changes of construction and arrangement that may be made without departing from the spirit and scope of my invention as defined in the appended claims.

What I claim as new and desire to secure by Letters Patent is:—

1. In a screen of the kind described, a frame enclosing a mesh, an oblique passageway comprising a diagonal bend in said frame, said diagonal bend being adapted to admit rays of daylight at a point where the diagonal bend joins the oblique passageway in a manner to attract insects on one side of said mesh to enter said passageway, 95 but not to lure insects on the outside to re-enter said passageway.

2. In a screen of the kind described, a frame enclosing a mesh, said frame consisting of top and bottom rails, stiles and a 100 molding, said top rail having a plurality of beveled portions, each of said beveled portions having a second bevel communicating directly with the atmosphere when the top rail is partly covered over by the molding, whereby an oblique passageway comprising a diagonal bend in the frame is provided, the bend serving to admit rays of

light up to a point where the bend joins the passageway, substantially as described.

3. In a screen of the kind described, a frame including top and bottom rails, styles 5 and a molding, a passageway formed between said molding and said top rail, said passageway communicating with an obliquely formed exit communicating directly with

the outer atmosphere, whereby rays of day-light may enter the oblique exit to a point 10 where it joins the passageway, substantially as described.

In testimony whereof I have signed my name to this specification.

RANDOLPH ARBUCKLE.
